CLAIM

The ornamental design for a telephone, as shown and described.

DESCRIPTION

FIG. 1 is a top plan view of a telephone showing my new design with the handset omitted in this view for clarity of presentation;

FIG. 2 is a front elevational view thereof, with the handset positioned in the stand;

FIG. 3 is a bottom plan view of the stand;

FIG. 4 is a partial left side, top, and front perspective view of the stand, with the handset spaced above the stand; and

FIGS. 5 and 6 are respectively right and left side elevational views of the assembled telephone.

The cord is omitted in sundry views for ease of illustration.

FIG. 1
